Inventor:
Edward L. Megill
By his Attorney
Frank J. Kent.

UNITED STATES PATENT OFFICE.

EDWARD L. MEGILL, OF NEW YORK, N. Y.

GRIPPER-FINGER.

1,400,303.

Specification of Letters Patent. Patented Dec. 13, 1921.

Application filed May 6, 1920. Serial No. 379,248.

To all whom it may concern:

Be it known that I, EDWARD L. MEGILL, a citizen of the United States, residing at New York, in the county of New York and 5 State of New York, have invented certain new and useful Improvements in Gripper-Fingers, of which the following is a specification.

The present invention is an improvement 10 in gripper fingers and which has been designed with the objects in view of enabling the engagement of the finger over the press gripper substantially at any point in the length thereof and the holding of the finger 15 at any desired point on the gripper.

Other objects have been to secure the finger to the gripper in such a way that it will be biased toward the platen and hence will firmly hold the paper and further to 20 provide a simple and practical hold-back for preventing the paper from following the finger as it recedes.

The invention involves a number of novel 25 features of construction, combinations and arrangements of parts, as will be disclosed in the course of the following specification.

In the drawing accompanying and forming a part of this specification I have illustrated the invention embodied in a practical 30 commercial form, but wish it understood that modifications may be made without departure from the true spirit and scope of the invention as defined in the appended claims.

35 In the drawing referred to, Figure 1 is a front or face view of the gripper finger;

Figs. 2, 3, and 4 are, respectively, end, edge and perspective views of the same;

Fig. 5 is a broken detail view of the upper 40 side of the gripper finger as applied and in position on the press gripper;

Figs. 6 and 7 are edge views illustrating the application of the finger to the gripper, the gripper appearing in section in both 45 instances.

The finger which is designated 10 may be of any desired length and width and the same is provided at the end where it is supported with a widened or enlarged base 50 portion 11, which is provided with, or carries, the means for attaching the finger 10 to the gripper 17. This base carries at the outer edge thereof an angularly projecting lug 12 and at the inner end thereof, at op- 55 posite sides of the root of the finger, the

abutments 13 and 14. The abutment 12 is shown as provided with an angularly bent flange 15 at its upper or outward edge and, similarly, the abutments 13 and 14 are shown as overturned at their outer terminals at 60 16, the latter forming short hooks for engagement with one edge of the press gripper 17 and the former providing a housing for the spring which engages the opposite edge of the press gripper. A special feature of 65 these abutments, which in use stand at opposite edges of the press gripper, is that they, including their hooked extremities, are spaced apart in the direction of the length of the finger a distance at least equal to 70 18 and preferably somewhat greater than the width of the press gripper—see particularly Figs. 5 and 7—so as to enable the engagement of the same flatwise over the gripper substantially at any point in the length 75 thereof.

18 designates a bowed spring which is secured intermediate its ends beneath the overstanding flange 15 of the abutment 12 by means of an outwardly struck looped 80 portion 19 formed in the back of the spring, the looped portion being engaged in an opening 20 in the upstanding side portion of the abutment and held therein by a part 21 of the flange indicated in Figs. 1 and 4 as depressed into the open side of said loop. This construction serves to securely anchor the spring without weakening the same and without interfering with its freedom of 85 action.

The free ends of the bow spring project 90 away from the supporting abutment and toward the coöperating abutments 13 and 14, and it is shown as provided at one end thereof with an angularly inturned pawl 95 22 for holding engagement with the edge of the gripper, which may be toothed or notched, while the other end of the bow spring is formed as a slide or shoe or skid 22'.

The free end of the finger 10 is maintained parallel to the press gripper by providing the spring 18 at one or both ends with angularly projecting lugs 23 inclined toward the base 11 (Fig. 3), and overstanding or overlapping the face of the gripper, as shown in Figs. 5 and 7, so as to exert a twisting effect which will tend to hold the base 11 against the flat side of the press gripper. This effect is obtained in the con- 100 105 110

struction illustrated by simply twisting or canting the free ends of the bow spring, as indicated at 24 in Fig. 1.

A further feature of the invention is the provision of what I call the finger spring, designated 25 and shown as consisting of a flat strip of spring metal having one end secured above and at the root end of the finger at 26 and projecting on an upward 5 incline or curve longitudinally toward the free end of the finger. During the printing operation the furniture in the chase, indicated at 27, will come into contact with the free end of spring 25, immediately before 10 the impression, the leverage of the spring lifting the median portion of the finger 10, at 26, and of course causing the free end of the finger 10 to move downwardly, thereby to hold the sheet firmly on the platen even 15 before the impression. And, because of this same leverage, as the furniture moves away from the platen the end of the finger 10 continues to hold the sheet down firmly until 20 spring 25 is completely disengaged from the furniture. 25

One of the principal advantages of the invention is that the gripper finger can be snapped into place over the press gripper at any desired point in the length thereof, 30 without manipulating any slides or the like and without the necessity for sliding the same endwise over the end of the gripper as has been the common practice heretofore. The gripper finger is particularly light, and 35 relatively inexpensive and is engaged on the gripper with a force which tends to hold it firmly thereon under all conditions.

I claim:—

1. The combination with a press gripper, 40 of a gripper finger having a unitary base provided with stationary angularly projecting abutments spaced in the direction of the length of the finger a distance at least equal to the width of the gripper to thereby enable engagement of the same flatwise over the gripper substantially at any point in the length thereof and a bowed spring supported by one of the abutments and projecting beyond said abutment toward the other 45 abutment to yieldingly engage the edge of the gripper. 50

2. The combination with a press gripper, 55 of a gripper finger having a unitary base provided with stationary angularly projecting abutments spaced in the direction of the length of the finger a distance at least equal to the width of the gripper to thereby enable engagement of the same flatwise over the gripper substantially at any point in the length thereof and a bowed spring supported by one of the abutments and projecting beyond said abutment toward the other abutment to yieldingly engage the edge of 60 the gripper, said spring having at one end thereof an inwardly turned holding pawl. 65

3. The combination with a press gripper, of a gripper finger having a base provided with angularly projecting abutments spaced in the direction of the length of the finger a distance at least equal to the width of the gripper to thereby enable engagement of the same flatwise over the gripper substantially at any point in the length thereof, a bowed spring supported by one of the abutments and projecting beyond said abutment toward the other abutment to yieldingly engage the edge of 70 the gripper and a finger-tensioning lug projecting angularly from the edge of spring on an incline toward the base to engage the flat side of the press gripper. 75

4. The combination with a press gripper, of a gripper finger having a unitary base provided with stationary angularly projecting abutments at the root of the finger and at opposite sides thereof and with a stationary abutment at the farther side of said base from said first two abutments, said abutment on the farther side being spaced from the first two abutments in the direction of the length of the finger a distance at least equal to the width of the gripper, and a bowed spring having its central portion secured to the single abutment on the farther side and its free ends projecting away from said abutment toward the first-mentioned abutments. 80

5. The combination with a press gripper, of a gripper finger having a base provided with angularly projecting abutments at the root of the finger and at opposite sides thereof and with an abutment at the farther side 85 of said base from said first two abutments, said abutment on the farther side being spaced from the first two abutments in the direction of the length of the finger a distance at least equal to the width of the gripper, and a bowed spring having its central portion secured to the single abutment on the farther side and its free ends projecting away from said abutment toward the first-mentioned abutments. 90

6. A gripper finger having a base portion engageable over a press gripper and provided with a flat spring having one end secured to the median portion of the finger at 100 the upper side thereof and its free end inclined upwardly away from the free end of the finger substantially as and for the purpose set forth. 105

7. A gripper finger having a base portion 110 provided with an angularly projecting lug having a pocket therein and a flange above said pocket, a spring for engaging the press gripper having a looped portion seated in said pocket and the overstanding flange of 115

the abutment being indented into said loop to thereby secure the spring to the abutment.

8. A device as described in claim 3, in which the ends of the bowed spring are twisted toward the base.

9. A gripper finger having a base portion engageable over the side of a press gripper and a bowed spring carried by said base por-

tion, said spring being supported at its central portion and arranged to engage with the edge of the press gripper at its free ends, angularly projecting lugs on the free ends of the spring and said free ends being twisted to incline said lugs toward the base referred to.

In testimony whereof I affix my signature.
EDWARD L. MEGILL.
